(57) **CLAIM**

The ornamental design for a control valve, as shown and described.

DESCRIPTION

2. Control valve
3. Control valve
4. Control valve
2.1: Back
2.2: Front
2.3: Right
2.4: Bottom
2.5: Top
2.6: Left
2.7: Perspective
3.1: Back
3.2: Right
3.3: Front
3.4: Bottom
3.5: Left
3.6: Top
3.7: Perspective

4.1: Back

4.2: Right

4.3: Top

4.4: Front

4.5: Left

4.6: Bottom

4.7: Perspective

The broken lines shown are included for the purpose of illustrating portions of the control valve that form no part of the claim.

1 Claim, 21 Drawing Sheets
